UNITED STATES PATENT OFFICE.

ROBERT S. BLAIR, OF NEW ROCHELLE, NEW YORK.

EYEGLASSES.

No. 841,614.

Specification of Letters Patent.

Patented Jan. 15, 1907.

Application filed October 26, 1906. Serial No. 340,645.

To all whom it may concern:

Be it known that I, ROBERT S. BLAIR, residing at New Rochelle, in the county of Westchester and State of New York, have 5 invented certain new and useful Improvements in Eyeglasses, of which the following is a full, clear, and exact description, such as will enable others skilled in the art to which it appertains to make and use the same.

10 This invention relates to eyeglasses.

One of the objects thereof is to provide a device of the above type of simple and practical construction and efficient action in use.

Another object is to provide a device of the 15 above type adapted to resist accidental dislodgment and evade tendency thereto.

Another object is to provide simple and inexpensive means in connection with glasses of the type first mentioned adapted to render 20 the same more comfortable to the wearer and to retain the same more securely in position.

Another object is to provide means connected with glasses of the relatively rigid frame type, whereby their construction is 25 simplified and their cost of manufacture reduced.

Other objects will be in part obvious and in part pointed out hereinafter.

The invention accordingly consists in the 30 features of construction, combinations of elements, and arrangements of parts, which will be exemplified in the embodiments hereinafter set forth and the scope of the application of which will be indicated in the following claims.

35 In the accompanying drawings, wherein are shown one or more of various possible embodiments of the several features of my invention, Figure 1 is a perspective view of a portion of one of the same. Fig. 2 is a plan of the same. Fig. 3 is a similar view of a slightly-different embodiment. Figs. 4 and 5 are detail views of a nose-engaging member.

Similar reference characters refer to similar 45 parts throughout the several views of the drawings.

In order to render clearer certain of the aims of this invention, it may be noted that in connection with rimless glasses, which are 50 now in somewhat broad use, the same are frequently dislodged from the face and broken by reason of the lenses being brushed in a direction away from the eye. Many glasses are so constructed as, upon the lens being 55 brushed in this direction to tend to sepa-

rate the nose-pads and loosen the hold upon the nose. It may also be noted that rigid-frame glasses are often considered objectionable by reason of their somewhat involved construction, tending to high first cost and a 60 difficulty to maintain the same in repair. It may also be noted that in connection with nose-engaging members or pads it is desirable that a given intensity of pressure should provide as large an engaging surface as is practicable, as in this manner a secure hold upon the nose is best insured. The above and other defects are remedied and the above and other advantages attained in constructions of the nature of that hereinafter described. 70

Referring now to Fig. 2 of the accompanying drawings, there are shown lenses 1 and 2, the latter of which is mounted in a holder 3 in rigid relation to the bridge 4. Secured upon the bridge adjacent lens 2 is a lever 5, 75 provided with a nose-pad 6, the construction of which will hereinafter be described in detail. Lever 5 is mounted upon the bridge, as by means of a screw 7, in such manner as to be clamped thereto at any desired angle, 80 and thus provide an attachment at this point. This lever, moreover, is so formed and constituted as to adapt the same to be bent slightly to accomplish small adjustments, and thus to a certain extent do away 85 with the necessity for the employment of the screw 7. At the opposite end of the bridge 4 there is pivotally mounted upon the pin 8 a lever 9, provided with a nose-pad 10 and adapted to swing with relation to the bridge, 90 the inward limit of this movement being determined by lug 11. Likewise journaled upon pin 8 is a lens-holder 12, adapted to permit the lens to swing outwardly from the corresponding eye, but to be limited as to 95 inward movement, as by the stop 13, in such manner as to maintain the lenses normally in the same plane. Lens-holder 12 is provided with an arm 14, normally disposed beneath a screw 15, tapped within the bridge beneath 100 the lever 9. A spring 16, substantially of the form shown, is positioned upon the screw 15 and tends normally to hold both the lever 9 and the lens-holder 12 against their respective stops. 105

The embodiment shown in Fig. 3 of the drawings differs from that above described mainly in that the lenses upon both sides are movable, as immediately above set forth, and the construction last described with ref- 110

erence to the modification shown in Fig. 2 obtains upon both sides in the modification shown in Fig. 3.

In order to aid in insuring a firm hold upon the nose with a minimum of pressure, a nose-pad 17 is employed, which may be riveted to its supporting member, as shown. This nose-engaging member is preferably of substantially the form shown, presenting a concave surface 18 to the nose, and is of such construction as upon engaging the nose to tend to flatten out and exert a substantially uniform pressure over the relatively large area thereof. This type of nose-pad, as will be seen, admits of the same fitting the nose snugly without previous adjustment to the wearer.

The operation of the above embodiments is substantially as follows: Assuming that it be desired to fit the glasses shown in Fig. 2, the lever 5 is first adjusted either by loosening the clamp 7 for large adjustments or by bending the lever for small adjustments, so as to properly position the nose-pad 6 to hold this side of the glasses in operative relation to the nose. This adjustment once being made it will be obvious that it is unnecessary to change the same for a given party. The glasses are placed upon the nose by drawing inwardly the outer end of the lever 9, as by drawing together the outer end of this lever and the abutment formed by the outer end of lever 5. The nose-pads are thus separated, so as to permit the glasses to be placed upon the nose, and upon the lever being released the reaction of spring 16 tends to throw the pad 10 toward the nose, so as to grip the same and hold the glasses in operative position. This feature of my invention is of value independent of its relation to the mechanism involving the mounting of the lens 1. With the glasses in position upon the face if the lens 1 be brushed away from the corresponding eye it will swing outwardly substantially freely, but will place additional tension upon the spring 16, tending to force inwardly the lever 9 and cause the nose-pads 6 and 10 to approach one another with a gripping action, which will absolutely prevent dislodgment. If the lens 2, moreover, be brushed in an outward direction, the same action will obtain to a greater or less extent, due to the swinging of the lens 1 against the corresponding eye, whereby the same is bent outwardly and spring 16 tensioned as above described.

In the form shown in Fig. 3 the operation in so far as it relates to gripping the nose and preventing dislodgment of the glasses should be largely clear from the matter above set forth, inasmuch as each lens tends upon swinging outwardly to force inwardly the corresponding nose-pad.

The action of the nose-pads 17 should be substantially clear from the matter already

set forth. These pads upon engaging the nose are of such flexible character as to flatten out thereon and obtain a large bearing surface, as already set forth.

It will thus be seen that I have provided devices in which the objects of my invention are achieved and the advantages already enumerated are, among others, present.

As many changes could be made in the above construction and many apparently widely-different embodiments of this invention could be made without departing from the scope thereof, it is intended that all matter contained in the above description or shown in the accompanying drawings shall be interpreted as illustrative and not in a limiting sense.

Having described my invention, what I claim as new, and desire to secure by Letters Patent, is—

1. In eyeglasses, in combination, a pair of lenses, a pair of nose-engaging members, a bridge, means connecting one lens with the corresponding nose-engaging member, a lever pivoted to said bridge leading from the same to the other of said nose-engaging members, a member holding the other of said lenses and journaled on said pivot, and a spiral spring having a horizontal axis and interposed between said last member and said lever and adapted upon said lens swinging outwardly to force said lever toward the nose.

2. In eyeglasses, in combination, a pair of lenses, a pair of nose-engaging members, a bridge, means connecting one lens with the corresponding nose-engaging member, a lever pivoted to said bridge leading from the same to the other of said nose-engaging members, a member holding the other of said lenses and journaled on said pivot, and a spiral spring having a horizontal axis and interposed between said last member and said lever and adapted upon said lens swinging outwardly to force said lever toward the nose, said connecting means comprising a member adapted to be bent to adjust the position of the corresponding nose-engaging member with relation to the bridge and maintain the same in adjusted position.

3. In eyeglasses, in combination, a bridge, a pair of lenses connected therewith, a lever pivoted with relation to said bridge and provided with a nose-engaging member, a spring tending to swing said lever to force said nose-engaging member toward the nose, a second nose-engaging member, and means connecting the same with said bridge whereby the same is adapted to be adjusted with relation thereto and maintained substantially rigidly in adjusted relation.

4. In eyeglasses, in combination, a bridge, a pair of lenses connected therewith, a lever pivoted with relation to said bridge and provided with a nose-engaging member, a spring tending to swing said lever to force said nose-

engaging member toward the nose, a second nose-engaging member, and means connecting the same with said bridge whereby the same is adapted to be adjusted with relation thereto and maintained substantially rigidly in adjusted relation, said last-mentioned means comprising a member which is adapted to be bent to vary the position of said nose-engaging member.

5. In eyeglasses, in combination, a bridge, a pair of lenses connected therewith, a lever pivoted with relation to said bridge and provided with a nose-engaging member, a spring tending to swing said lever to force said nose-engaging member toward the nose, a second nose-engaging member, and means connecting the same with said bridge whereby the same is adapted to be adjusted with relation thereto and maintained substantially rigidly in adjusted relation, said nose-engaging members being of flexible, resilient character, and presenting to the nose a concave surface whereby the same are adapted to partially flatten against the nose.

10. In a pair of eyeglasses, in combination, a bridge, lens-holding means mounted upon the end of said bridge adjacent thereto and adapted to swing with reference thereto, means comprising a nose-engaging member connected with said end of said bridge and adapted to swing with reference thereto, and means interposed between said lens-holding means and said second means adapted upon the lens within said lens-holding means swinging away from the corresponding eye to tend to press said nose-engaging member toward the side of the nose upon which said means is mounted.

15. In a pair of eyeglasses, in combination, a bridge, lens-holding means mounted upon the end of said bridge adjacent thereto and adapted to swing with reference thereto, means comprising a nose-engaging member connected with said end of said bridge and adapted to swing with reference thereto, and means comprising a spring interposed between said lens-holding means and said second means adapted upon the lens within said lens-holding means swinging away from the corresponding eye to tend to press said nose-engaging member toward the side of the nose upon which said means is mounted.

20. In a pair of eyeglasses, in combination, a bridge, means comprising a nose-engaging member mounted upon said bridge and adapted to swing with reference thereto, lens-holding means mounted upon said bridge and adapted to swing with reference thereto, and means interposed between said first and second mentioned means adapted upon said lens-holding means being swung outwardly about its axis to tend to cause said first means to swing in the opposite direction about its axis.

25. In a pair of eyeglasses, in combination,

a bridge, lens-holding means mounted upon the end of said bridge adjacent thereto and adapted to swing with reference thereto, means comprising a nose-engaging member connected with said end of said bridge and adapted to swing with reference thereto, means comprising a spring interposed between said lens-holding means and said second means adapted upon the lens within said lens-holding means swinging away from the corresponding eye to tend to press said nose-engaging member toward the side of the nose upon which said means is mounted, and means comprising a nose-engaging member connected with the opposite end of the bridge and adapted to engage the opposite side of the nose.

30. In a pair of eyeglasses, in combination, a bridge, means comprising a nose-engaging member mounted upon said bridge and adapted to swing or rotate with reference thereto, lens-holding means mounted upon said bridge and adapted to swing or rotate with reference thereto about a substantially parallel axis, and means interposed between said first and second mentioned means adapted upon said lens-holding means being rotated in one direction about its axis to tend to rotate said first means in the opposite direction about its axis.

35. In a pair of eyeglasses, in combination, a bridge, means comprising a nose-engaging member mounted upon said bridge and adapted to swing or rotate with reference thereto, lens-holding means mounted upon said bridge and adapted to swing or rotate with reference thereto about a substantially parallel axis, and means comprising a spring interposed between said first and second mentioned means adapted upon said lens-holding means being rotated in one direction about its axis to tend to rotate said first means in the opposite direction about its axis.

40. In a pair of eyeglasses, in combination, a bridge, means comprising a nose-engaging member mounted upon said bridge and adapted to swing or rotate with reference thereto, lens-holding means mounted upon said bridge and adapted to swing or rotate with reference thereto about a substantially parallel axis, means interposed between said first and second mentioned means adapted upon said lens-holding means being rotated in one direction about its axis to tend to rotate said first means in the opposite direction about its axis, lens-holding means mounted upon the opposite end of said bridge, a lens within each of said lens-holding means, and a stop adapted to limit the inward swinging of said first lens-holding means in a position in which said glasses are in the same plane.

45. In a pair of eyeglasses, in combination, a bridge, means comprising a nose-engaging

member mounted upon one end of said bridge and adapted to swing with reference thereto, lens-holding means mounted upon the same end of said bridge and adapted to swing with reference thereto, a spring having a transverse axis interposed between said first and second mentioned means and adapted upon said lens-holding means being swung outwardly to tend to swing said nose-engaging member toward the adjacent side of the nose.

14. In a pair of eyeglasses, in combination, a bridge, a lens-holder pivoted to one end thereof, a nose-engaging member, a member pivoted to said end of said bridge and having mounted thereon said nose-engaging member, a spring operatively connected with said lens-holding means and with said second member mounted upon said bridge, said spring being adapted upon said lens-holding means being swung outwardly to force said nose-engaging member toward the adjacent side of the nose, and a stop adapted to arrest the inward swinging of said lens-holder in a predetermined position.

15. In a pair of eyeglasses, in combination, a bridge, a lens-holder pivoted to one end thereof, a nose-engaging member, a member pivoted to said end of said bridge and having mounted thereon said nose-engaging member, a spring operatively connected with said lens-holding means and with said second member mounted upon said bridge, said spring being adapted upon said lens-holding means being swung outwardly to force said nose-engaging member toward the adjacent side of the nose, and a stop adapted to arrest the inward swinging of said lens-holder in a predetermined position, a portion of said spring intermediate said second member and said lens-holding means being mounted upon said end of said bridge.

16. In a pair of eyeglasses, in combination, a bridge, a pair of nose-engaging members, a pair of lenses mounted upon said bridge, means connected with one of said nose-engaging members and mounted upon said bridge to permit said nose-engaging member to swing with reference thereto, and means connecting the other of said nose-engaging members to said bridge and holding the same in substantially rigid relation thereto whereby the glasses may be placed upon the nose by the outward swinging of a single nose-engaging member.

17. In a pair of eyeglasses, in combination,

a bridge, a pair of nose-engaging members, a pair of lenses mounted upon said bridge, means connected with one of said nose-engaging members and mounted upon said bridge to permit said nose-engaging member to swing with reference thereto, and means connecting the other of said nose-engaging members to said bridge and holding the same in substantially rigid relation thereto whereby the glasses may be placed upon the nose by the outward swinging of a single nose-engaging member, said second-mentioned means being adapted to be bent to adjust the position of the corresponding nose-engaging member with reference to the other of said nose-engaging members.

18. In a pair of eyeglasses, in combination, a bridge, a pair of nose-engaging members, a pair of lenses mounted upon said bridge, means connected with one of said nose-engaging members and pivotally mounted upon said bridge to permit said nose-engaging member to swing with reference thereto, a spring tending to swing said nose-engaging member toward the nose, and means connecting the other of said nose-engaging members to the bridge and holding the same in substantially rigid relation thereto whereby the glasses may be placed upon the nose by the outward swinging of a single nose-engaging member.

19. In a pair of eyeglasses, in combination, a bridge, a pair of nose-engaging members, a pair of lenses mounted upon said bridge, means connected with one of said nose-engaging members and pivotally mounted upon said bridge to permit said nose-engaging member to swing with reference thereto, a spring tending to swing said nose-engaging member toward the nose, and means connecting the other of said nose-engaging members to the bridge and holding the same in substantially rigid relation thereto whereby the glasses may be placed upon the nose by the outward swinging of a single nose-engaging member, said second means being adapted to be bent to adjust the position of the corresponding nose-engaging member with reference to the other of said nose-engaging members.

In testimony whereof I affix my signature in the presence of two witnesses.

ROBERT S. BLAIR.
